Attorney

UNITED STATES PATENT OFFICE.

JOHN R. DAVIS, OF SEATTLE, WASHINGTON.

TEETER BOARD.

Application filed August 22, 1921. Serial No. 494,249.

To all whom it may concern:

Be it known that I, JOHN R. DAVIS, a subject of the King of England, residing at Seattle, in the county of King and State 5 of Washington, have invented certain new and useful Improvements in Teeter Boards, of which the following is a specification, reference being had to the accompanying drawings.

10 It is the purpose of the present invention to provide a device of this kind, which may be used indoor or outdoor, and is particularly adapted for use at amusement places, or on playgrounds.

15 Another purpose consists in the provision of a device of this general character, wherein the teeter board is mounted upon a base to support the board for rocking movement, there being yieldable means for connection 20 between the base and the board, so that the board may be oscillated in a vertical plane, there being handles or grips adjacent the opposite ends of the board to hold those who may be operating the board in position and 25 assist materially in preventing them from falling off.

Still another purpose is to provide a device of this kind, which may be constructed so that it is portable from one place to another, the base thereof being employed to 30 protect the floor covering or floor from wear, when the teeter board is operated indoors.

A further purpose consists in the provision of a support, on which the board oscillates, there being springs or other yieldable 35 means mounted on the support and having arms projecting from the coils of the springs to engage between the board and the base of the support, so that the springs will counteract each other when the board is oscillated.

While the design and construction at present illustrated and set forth are deemed preferable, it is obvious that as a result of a 45 reduction of the invention to a more practical form for commercial purposes, the invention may be susceptible of changes, and the right to these changes is claimed, provided they are comprehended within the 50 scope of what is claimed.

The invention comprises further features and combination of parts, as will be hereinafter set forth, shown in the drawings and claimed.

In the drawings:

Figure 1 is a view in elevation showing the teeter board constructed in accordance with the invention;

Figure 2 is a vertical sectional view on line 2—2 of Figure 1;

Figure 3 is a view in elevation of a modified form of teeter board, showing one of the supports 15 removed, and wherein the yieldable connections between the board and the base of the support are slightly modified;

Figure 4 is a sectional view on line 4—4 of Figure 3;

Figure 5 is a view in side elevation of another form of teeter board, wherein is a single yieldable device, such as a leaf spring connecting between the base and the support of the teeter board, to counterbalance the operator; and

Figure 6 is a sectional view on line 6—6 of Figure 5.

Referring to the drawings, particularly Figures 1 and 2, 1 designates a base which is provided with side flanges 2 arranged in pairs, and between which the rockers are 80 operable. It is obvious that the teeter board may be constructed to be used outdoors, and in this case the base may be constructed accordingly. However it is obvious that the teeter board may be used indoors, either in 85 gymnasiums or in enclosures at amusement places, or may be portable from one place to another, and may be used in the rooms, particularly the play rooms of private homes, and in this latter case the base materially assists in preventing wear on the floor 90 or floor covering.

The lower curved portions or arches (which engage between the side flanges 2) of the rockers are connected by a transverse 95 bar 3. The ends of this transverse bar 3 are riveted to the curved or arcuate portions of the rockers as at 5. The arms of the rockers diverge upwardly, and secured to their upper ends as at 6 is a board 7, the opposite 100 ends of which are constructed with seats 8 for the operators, one to counterbalance the other. The opposite edges of the board 7 adjacent the seats are provided with cut away portions 9 of arcuate form similar to 105 the cut away portions 23, so as to accommodate the legs of the operators when occupying the seats with their legs straddling the

board. Rising upwardly from the board 7 adjacent the cut away portions 9 are arched handles 10, which may be grasped, assisting materially in holding the operators on the seats.

Connected to the under surface of the board, as at 11 are coil springs 12, which converge downwardly toward and are connected detachably at 13 to the base. These 10 springs are alternately stretched and contracted as the board oscillates, and assist materially in imparting movement to the board, as well as counteracting each other, to assist in imparting oscillatory movements 15 to the boards.

In Figures 3 and 4 the teeter board is modified, and in this instance the base 14 has upstanding supports 15, on the arcuate surfaces 16 of the heads 17 of which the board 20 18 oscillates.

The supports are provided with the laterally extending heads 20. In the form of teeter board shown in Figures 3 and 4 the board 21 rocks upon the arcuate surfaces of the lateral heads 20, and is provided with a single seat 22 for a single operator. In this case the opposite edges of the board adjacent the seat 22 is provided with arcuate cut away portions 23 for the reception of the legs of the operator. Though the board is provided with a single seat, it is obvious that the board may have two seats, one at each end. Connecting the opposite edges of the board and rising upwardly therefrom is a 30 U-shaped or arched handle 24 to be grasped by the operator to support the operator in position. Should the board 21 be provided with two seats, two handles would be employed.

Extending axially through the heads 20 and having means on its opposite ends to prevent axial movement is a shaft or rod 25, and mounted thereon are coil springs 26. The ends of these coil springs terminate in elongated arms 27 and 28. The arms 27 are slidably connected to the under surface of the board 21, while the arms 28 are connected to the base 14.

It will be noted that the spring arms 27 and 28 on one side of the supports will counteract corresponding arms on the other side of the supports, therefore acting to counterbalance the operator, when oscillating the board 21. In case the board 21 has a single seat, it is obvious that one of the coil springs and its arms 27 and 28 nearest the seat 22 are constructed of relatively heavy spring metal, so that when the board is free of an operator, the board will be in-

clined upwardly. However as soon as an operator occupies the seat 22, the yieldable means of the device on both sides of the supports will then act to counteract each other, and at the same time counterbalance the operator.

In Figures 5 and 6 a pair of supports 30 rise upwardly from a base 30^a, and mounted in the supports and connecting them is a pair of bolts 31 and 34, the former of which is slightly larger in diameter, to provide a firm bearing for the board 29. The board 29 has a single seat 32, and a handle 33. A relatively heavy leaf spring 35 is secured at 36 to the base 30^a, and rests upon the lower bolt 34, and has its other free end slidably 75 engaging the lower surface of the board 29 adjacent the seat.

This spring 35 also holds the board normally in an inclined position, when the seat 32 is unoccupied. However when the seat 32 is occupied the action of the spring 35 will be overcome by the weight of the operator and then will act to not only counterbalance the board, but also the operator when oscillating the board.

The invention having been set forth, what is claimed as being useful is:

In a teeter board, a relatively short base having upstanding parallel side flanges extending longitudinally of the base and being of uniform height throughout their length, an oscillatory board, rockers comprising upwardly diverging arms secured to the under face of the board, whereby the rockers assume positions substantially midway between the ends of the board, the lower portions of the rockers terminating in arcuate portions which rock upon the base in such wise as to engage the inside faces of the flanges, which act to prevent lateral movement of the arcuate portions as they rock back and forth on the base and to retain the arcuate portions in engagement with the base, a transverse brace rod rigidly connecting the arcuate portions of said rockers to reinforce and hold the rockers in register, said rod being disposed centrally of the arched portions, so as to assume a position below the upper edges of said retaining flanges, yieldable means comprising springs connected to the opposite ends of the base and being diverged upwardly from the base and in turn connected to the opposite ends of the board, and seats on the opposite ends of said board.

In testimony whereof I hereunto affix my signature.

JOHN R. DAVIS.
